BOILER RETURN TRAP

John M. Dougherty, St. Louis, Mo.

Application June 22, 1934, Serial No. 731,826

14 Claims. (Cl. 103—252)

My invention relates to automatic boiler return devices for low pressure steam heating or like systems wherein steam is alternately admitted to a vacuum return tank and condensed 5 therein to exhaust air from the system and, in some installations, to pump water of condensation from the radiators to the boiler.

The main object of my invention is to drive all the air from the vacuum condensation tank 10 before condensing the steam therein to draw air or water from the system.

Another object of my invention is to reduce the amount of vacuum or power required for returning the condensation, drawn from the system, to the boiler.

Another object of my invention is to accelerate the condensation of steam in the vacuum condensing tank by exposing the same to contact with water of lower temperature than water 20 which has been in contact with the steam.

In the accompanying drawing which illustrates a selected construction embodying the invention—

Figure 1 is an elevation and section of a condensing tank and equipment associated therewith embodying one form of my invention.

Figure 2 is a detail of the thermostatic control and the air relief valve structure whereby one source of supply of steam into the condensing tank is controlled.

Figure 3 is a detail of the steam valve actuated by the thermostatic control.

In the construction illustrated, the vacuum condensing tank is shown at 1. Piping 2 leads from the heating system (not shown) to the tank and includes an upstanding portion 3 having an open end 4 spaced a short distance from the top of tank 1 and substantially above the highest water level reached in the tank. Piping 5 leads 35 from the lower portion of tank 1 to the boiler (not shown) and piping 5 is substantially larger than piping 2. Pipe 6 between piping 2 and 5 provides for complete circulation in the heating system independently of the vacuum tank structure.

Check valves 7, 8 and 9 permit water and steam to flow freely in the directions indicated by the arrows A, B and C, respectively, and positively prevent the flow of fluid in the opposite direction. A pressure check valve V is located 40 at the inlet end of piping 5 and closes against movement of fluid into the tank therethrough.

A relatively small cooling chamber 10 is located adjacent the left hand end of tank 1 and is connected therewith by a series of pipes 11 disposed at different levels. A series of flues F

extend through tank 1 and chamber 10 and the passage of air through these flues is controlled by a damper D.

A thermostatic regulator device 13 is mounted on chamber 10 and is exposed to the temperature therein. Member 13 is of well known construction and includes a bellows which expands when heated to move finger 14 upwardly. This raises the left hand portion of a lever 17 pivoted at 13. A spring actuated air relief valve 12 on chamber 10 5 is controlled by lever 17 to which it is connected by link 12a.

A valve 15 controls the passage of steam from a pipe S through a pipe 19 to a perforated pipe 20 which is disposed vertically near the right hand end of the boiler and discharges steam thereinto at different levels substantially throughout the depth of the boiler. Valve 15 is connected by an arm 16 to the end of lever 17. 15

When the regulator finger 14 moves upwardly, 20 lever 17 positively closes air relief valve 12 and also closes steam valve 15. At the same time, lever 17 opens the damper D, permitting the flow of air into flues F extending through chambers 10 and tank 1. A flue F' leads from the right 25 hand end of tank 1 to the chimney, thereby creating a draft through the flues.

Another steam inlet valve 21 functions independently of valve 15 to admit steam from pipe S direct to the tank. Valve 21 is of familiar form 30 and is controlled by a weighted arm 22 actuated by a float 23 which rises and falls with the water level in condensing tank 1. When float 23 rises, valve 21 is opened. When float 23 falls, valve 21 is closed. An air relief valve 28 functions automatically to vent air which may gather in the tank. Another air relief valve 24 functions similarly to vent air from the return system. 35

Operation:—Assume that the boiler is cold and tank 1 is filled with air. The bellows in the regulator 40 10 is contracted and finger 14 is in its lowermost position. Air relief valve 12 and steam valve 15 are open and steam valve 22 is closed. When the boiler is fired, the first steam generated will pass through valve 15 and pipe 19 and be 45 discharged at 26 at the right hand end of the tank and will force the air therein to the left through tubes 11 into chamber 10 and out of air relief valve 12 until tank 1 is filled with steam, when the same will contact with the bulb in thermostatic device 13, expanding the bellows and shifting lever 17 which closes air relief valve 12 and steam valve 15 and opens damper D, all as described above. 50

The steam in the tank being exposed to the 55

room temperature will condense, creating a partial vacuum in the tank which draws water through pipe 3 into the tank until the water level in the tank raises float 23 sufficiently to open valve 21. This will admit a fresh supply of steam to the tank, placing the same under boiler pressure which will close check valve 7 and open valves V and 8, and the water in the tank will be forced into the boiler.

10 As the water level in tank 1 falls, float 23 is lowered until valve 21 snaps to closed position, the tank being substantially filled with steam which then condenses, creating a partial vacuum resulting in the closing of valve V and the opening of valve 7 and the drawing in of an additional supply of water through piping 3. As the water level rises, lifting float 23, the cycle of operations is repeated.

15 The check valve V at the entrance to pipe 5 insures that the vacuum in tank 1 will draw water from pipe 3 exclusively. That water will be substantially cooler than the water in pipe 5 and this results in more rapid condensing of the steam and a higher degree of vacuum than would 20 result if water from pipe 5, previously heated by the steam in tank 1, was drawn into the vacuum tank. The extension of pipe 3 to the upper part of the tank provides that all of the water drawn into the tank will contact with the steam before 25 being heated by the water previously admitted which has had its temperature raised by the steam. This contributes to more rapid condensation of the steam in the tank throughout the period water is being admitted.

30 35 By making the water inlet piping 3 of smaller diameter than the piping 5 leading to the boiler, a differential is created which facilitates the raising of the water through piping 3, by reducing the weight to be overcome, and facilitates the discharge to the boiler, by increasing the rate of 40 flow from the tank.

45 By delivering the steam at the far end of the condensing tank 1 and at the varying levels, the steam fills the tank, forcing all the air in the tank ahead of it out through the cooling chamber 10, but the steam does not come in contact with the regulating device 13 until the condensing tank 1 is entirely free of air, and when the steam does 50 come in contact with the regulating device, it brings the regulator into operation to close off the steam valve 15, and with the same action to close off the atmospheric air valve 12, preventing a waste of steam.

55 The device may be applied to a heating system in which the vacuum tank is applied to the air line leading from the radiator to accelerate the passage of steam from the boiler and to draw water into the lower portion of the boiler rather than to pump it into the boiler under steam 60 pressure. The function of the device is somewhat different but the operation is very similar.

65 Piping 5 will be discarded and piping 3 will be connected to the line leading from the air valves on the radiators. Valve 21 and its float control will be omitted. In starting operation, the first steam admitted to the tank will drive out the air therein through valve 12. When the steam reaches regulator 13 it closes valves 12 and 15. The steam in the tank then condenses, drawing 70 air in from the heating system which will tend to cool the bulb in the regulator 13, resulting in shifting lever 17 so as to open steam valve 15 and air relief valve 12. The boiler pressure will close valve 7 which will remain closed until 75 sufficient steam is present in tank 1 and chamber

10 to heat the thermostatic regulator to again shift lever 17 to close valves 12 and 15.

Repetition of this cycle exhausts the air in the heating system and draws water into the boiler through the water return line which is directly connected to the boiler below the water line.

15 Each of the installations described embodies the widely spaced arrangement of the steam inlet and air relief and thermostatic regulator and the 20 separate chamber for the latter, and utilizes the simultaneous mechanical closing of the air relief and steam inlet valves.

25 The details may vary other than as described without departing from the spirit of the invention and I contemplate the exclusive use of those 30 modifications which come within the scope of my claims.

I claim:

1. In a structure of the class described, a condensing tank, means for admitting water to said tank and for discharging water therefrom, means for supplying steam to said tank at one end thereof, an air relief valve, and a thermostatic device for controlling said valve, said valve and device being located adjacent the opposite end of said tank.

2. In a structure of the class described, a condensing tank, means for admitting water to said tank and for discharging water therefrom, means for supplying steam to said tank at one end thereof, said means including a steam valve, an air relief valve, and a thermostatic device for controlling both of said valves, said air relief valve and said device being located adjacent to the opposite end of said tank.

3. In a structure of the class described, a condensing tank, means for admitting water to said tank and for discharging water therefrom, means for supplying steam to said tank, said means including a steam valve, an air relief valve, and a thermostatic device for closing and opening both of said valves simultaneously.

4. A device as described in claim 3 which includes a second means for supplying steam to the tank, a valve therefor, and a float in the tank for opening and closing said latter-mentioned valve according to the water level in the tank and independently of the operation of the thermostatic device.

5. In a structure of the class described, a condensation tank, means for admitting water to said tank and for discharging water therefrom, a substantially smaller chamber spaced from one end of said tank, tubes providing restricted passages between said tank and chamber, a thermostatic regulator device adjacent to said chamber and connected therewith, a steam pipe discharging into the other end of said tank, and a valve controlled by said regulator for said pipe.

6. A structure as described in claim 5 which also includes an air relief valve leading from the smaller chamber, and means actuated by the regulator device for positively closing said air relief valve as the steam valve is closed.

7. In a structure of the class described, a condensation tank, means for admitting water to said tank and for discharging water therefrom, a steam supply pipe having a discharge orifice in said tank, a valve for said pipe, means for venting air from said tank, a steam-actuated thermostatic regulator for closing said valve, and means between said orifice and said regulator for delaying the functioning of said regulator until said tank is freed of air.

8. In a structure of the class described, a condensation tank, means for admitting water to said tank and for discharging water therefrom, a chamber spaced from one end of said tank, an air relief valve and a thermostatic regulator in said chamber, said chamber being substantially smaller in volume than said tank but substantially equal to said tank in depth, there being a plurality of tubes disposed at different levels and forming restricted passages between said tank and chamber. 5
9. In a structure of the class described, a condensing tank, means for admitting water to said tank and for discharging water therefrom, a supplementary chamber spaced therefrom, means for supplying steam to said tank, and a thermostatic device actuated by the presence of steam in said chamber for shutting off the flow of steam to said means. 10
10. In a device of the class described, a condensing tank, means for supplying steam to said tank, means for admitting water to said tank and for discharging water therefrom, a thermostatic device spaced from said tank and arranged 15 to shut off said means, and means for conducting steam from said tank to said thermostatic device only after said tank has been substantially filled with steam. 20
11. In a structure of the class described a condensation tank, means for admitting water to said tank and for discharging water therefrom, means for supplying steam to the interior of said 25
- tank adjacent one end thereof, a thermostatic device spaced outwardly from the other end of said tank, and means for conveying steam from the latter-mentioned end of said tank to said device. 5
12. In a structure of the class described, a condensation tank, means for admitting water to said tank and for discharging water therefrom, a separate chamber spaced outwardly from one end of said tank, a thermostatic device mounted 10 on said chamber, an air relief valve mounted on said chamber, a valve for admitting steam to said tank, and an arm actuated by said thermostatic device when the latter is heated for simultaneously closing said air relief valve and said 15 steam valve. 20
13. In a structure of the class described, a condensing tank, means for admitting water to said tank and for discharging water therefrom, a steam supply pipe provided with an orifice device arranged to discharge steam substantially throughout the depth of said tank at one end thereof. 25
14. In a structure of the class described, a condensing tank, means for admitting water to said tank and for discharging water therefrom, a steam supply pipe extending downwardly into said tank at one end thereof and perforated to discharge steam into said tank at different levels substantially throughout its depth. 30
